TROUSERS CONSTRUCTION

Jack A. Winter, Milwaukee, Wis.

Application February 17, 1936, Serial No. 64,275

4 Claims. (Cl. 2—232)

This invention relates to improvements in trouser construction.

The present invention has particular reference to the lower ends of trouser legs and provides a novel construction whereby a retailer, after a sale has been made, can quickly form a desired cuff on the trousers leg bottom and at the same time make the trousers of requisite length to fit the purchaser. Heretofore, in order to have a suitable stock on hand, it has been necessary for a merchant to carry trousers in a plurality of different lengths for each type of material, and it has also been essential to have tailoring service available in order to properly form the cuffs to fit each individual purchaser. With the present invention it is necessary to carry only one, or at the most two lengths for each type of material, and it is unnecessary to employ a tailor to finish the cuffs as this can be accomplished by simple folding and pressing operations, and in certain instances by ripping out a line of stitching. As a result, the present invention is especially advantageous to the small dealer who sells odd trousers, as this type of merchant cannot afford expensive alteration or fitting operations and cannot afford to keep on hand a large stock of various lengths.

It is therefore a general object of the present invention to provide an improved trousers wherein the leg bottoms are so constructed as to provide for the quick formation of cuffs thereon and for control of the final length of the leg portions, without necessitating the use of tailoring service.

With the above and other objects in view, the invention consists of the improved trousers construction and all its parts and combinations as set forth in the claims and all equivalents thereof.

In the accompanying drawing in which the same reference numerals designate the same parts in all of the views:

Fig. 1 is a view, partially in perspective, showing the lower end of a trousers leg constructed in accordance with the present invention;

Fig. 2 is fragmentary longitudinal sectional view of the lower end of a trousers leg showing the trousers without a cuff thereon;

Fig. 3 is a similar view showing a cuff formed on the trousers;

Fig. 4 is a similar view showing the cuff rolled downwardly to lengthen the trousers;

Fig. 5 is a similar view showing how the material is dropped down preparatory to forming a still longer trousers leg;

Fig. 6 is a similar view showing a cuff formed on the trousers leg of Fig. 5;

Fig. 7 is a view similar to Fig. 2 showing a modified form of construction;

Fig. 8 is a similar view showing a cuff formed on the trousers leg of Fig. 7; and

Fig. 9 is a similar view showing how the trousers leg of Fig. 8 may be lengthened.

Referring more particularly to Figs. 1 to 6 of the drawing, the numeral 12 designates a fragment of the lower portion of a trousers leg, and it will be seen that at the bottom of the leg portion the material is folded upwardly within the leg portion to form a first fold section 13. The same material is then folded downwardly from the line 14, between the inside of the leg portion and the first fold section to form a second fold section 15. The second fold section 15 is then preferably folded upwardly again to form a third fold section 16, and the upwardly projecting free edge 17 of the third fold section is secured to the inner side of the trousers leg 12 by a line of felling 18. The upper edge 14 of the first fold section 13 is also connected to the inside of the leg portion 12 by a line of felling 19.

The trousers leg bottom thus formed is illustrated in Fig. 2, and it is in this manner that the retailer may receive the trousers from the manufacturer. When a sale is made, if the purchaser requires the shortest length of trousers, then it is merely necessary for the dealer to fold the material upwardly from the position of Fig. 2 to the position of Fig. 3 to provide a cuff 20, and this cuff may then be pressed in position and possibly tacked in one or two places.

If a somewhat longer trousers leg is necessary, then the cuff 20 shown in Fig. 3 may be rolled downwardly to the position of Fig. 4 and then pressed and tacked in position. The amount of rolling is limited only by the position of the line of felling 18 as it is not desirable to roll the cuff downwardly to such a position that this line of felling is exposed on the exterior of the cuff. It is for this reason that the third fold section 16 (see Fig. 2) is provided, and the amount of rolling possible without exposing the line of felling 18 depends upon the length of the third fold section 16.

To obtain a trousers leg of still greater length then instead of folding the trousers bottom of Fig. 2 upwardly to the position of Fig. 3, the line of felling 18 is ripped out and the material held thereby is dropped down to the position of Fig. 5. Then to form the cuff it is merely necessary to fold the material at the bottom of the trousers of

Fig. 5 to the position of Fig. 6 to provide a cuff 21. It will thus be seen that the three finished trousers legs of Figs. 3, 4 and 6 vary substantially from one another in length. It is therefore possible by carrying a single trousers with the bottom constructed as shown in Fig. 2 to provide, for example, for the formation of trousers lengths of either 30, 31 or 32 inches.

It is not essential that provision be made for 10 rolling of the cuff from the length of Fig. 3 to the length of Fig. 4, and where such variation is not desired, the third fold section 16 can be eliminated. When this is done, the trousers leg is convertible only from the length of Fig. 3 to 15 the length of Fig. 6.

In Figs. 7, 8 and 9 a slightly modified construction is illustrated wherein an additional length variation is made possible through the use of a tuck. Referring first to Fig. 7, which illustrates 20 the form in which the trousers legs are sent to the retailer, it will be seen that the construction is identical to Fig. 2 except that there is a tuck 22 formed on the exterior of the leg portion 12, which tuck has its folded edge 23 projecting 25 downwardly. The tuck is preferably held in position by a line of removable stitching 24.

If trousers formed in this manner are stocked by the retailer and he desires to provide the shortest leg length, then the material is merely folded 30 upwardly exteriorly of the trousers from the position of Fig. 7 to the position of Fig. 8, to form a cuff 25. This cuff may then be pressed and tacked in position. If a somewhat longer trousers leg is desired, it is merely necessary to rip out 35 the line of stitching 24 and let out the tuck to the position of Fig. 9. It is to be noted in Fig. 8, that the tuck 22 is entirely concealed by the cuff and that by having the tuck project downwardly that a smooth cuff effect can be obtained without causing the cuff to be unnecessarily bulky.

40 The modified form of trousers construction can be changed to still greater lengths by rolling the cuff 25 of Fig. 9 downwardly in the same manner in which the cuff of Fig. 3 is rolled to the position of Fig. 4, and still further variation in length can 45 be obtained, as in the principal form of the invention, by ripping out the line of felling 19 (Fig. 7) so that the trousers bottom can be finished in the manner illustrated and heretofore described 50 in connection with Figs. 5 and 6 to produce a trousers leg of maximum length.

55 It is apparent that none of the operations above described require the use of a tailor and that in all forms of the invention a neat appearing cuff of standard width can be obtained.

The invention is adapted for use on trousers formed of various materials such as worsted, flannel, cotton, and the like, and is particularly well 60 adapted for use on wash trousers which are subject to shrinkage. In this adaptation of the invention the trousers may be furnished to the buyer finished in one of the shorter lengths, and if after washing, shrinkage occurs, the user can readily lengthen the trousers legs himself without 65 impairing the appearance.

In a similar manner, the invention is particularly well adapted for use in connection with trousers for growing boys. The garment may be 70 originally purchased with the trousers legs finished in one of the shorter lengths, and as the boy's height increases the length of the trousers legs may be readily increased, through the use of the present invention, without in any way affecting the appearance.

75 When the trousers are finished in the manner

shown in Figs. 3, 4, 8 or 9, it is to be noted that there are more thicknesses of material in the cuff than is standard practice. This is advantageous as the additional weight causes the trousers to hang better and also makes the crease 5 last for a longer period.

It is to be understood that the trousers may be furnished to the retailer in either the manner shown in Figs. 2 or 3. If the trousers are being 10 sold separately, which is customary in connection with sport trousers, slacks, and the like, then they will probably be furnished to the retailer in the manner shown in Fig. 3 with the cuff formed thereon. Thus if the length is proper for the 15 purchaser, no alteration at all is necessary. If, however, a longer length is necessary, then the cuff of Fig. 3 can be readily converted to one of the other lengths shown in Figs. 4 and 6.

It is obvious that stitching or felling may be 20 used interchangeably, the description and drawing merely referring to the preferred manner of securing the folded sections in position. Various other changes and modifications may be made without departing from the spirit of the invention, and all of such changes are contemplated as 25 may come within the scope of the claims.

What I claim is:

1. A variable length trousers construction comprising tubular leg portions, the lower end of the material of each leg portion having a plurality 30 of reversely extending folds on the inside of the trousers, means for securing the free edge of the material between the inside of the leg portion and one of said folds, and other means for removably holding said folds in position located a substantial distance upwardly on the inside of the leg and spaced at least the width of the cuff to be formed above said securing means for the free edge of the material whereby when said removable means is in place, the lower edge of the 40 trousers leg may be folded exteriorly to form a cuff without exposing said means for removably holding the folds in position, said trousers leg being readily formable to greater length by removing said removable means and letting down 45 the material held thereby and by subsequently folding said material exteriorly upwardly to form a cuff from different portions of the material than used in the first mentioned cuff.

2. A variable length trousers construction comprising tubular leg portions, the lower end of the material of each leg portion having a first fold section extending upwardly within the leg portion and having a second fold section extending continuously downwardly therefrom between the 55 inside of the leg and said first fold section, removable means extending along the upper edge of said first fold section for securing said edge to the inside of the trousers leg, and means for securing the free edge of the material forming 60 said second fold section to the material of the leg portion, the trousers bottom being foldable exteriorly upwardly to form a cuff, and the removable means at the upper edge of the first fold section being so positioned that it will not be exposed when said cuff is formed, and said trousers being formable to greater length by removing 65 said removable means and letting down the edge formerly held thereby, and by subsequently folding said edge upwardly exteriorly of the trousers 70 to form a cuff.

3. A variable length trousers construction comprising tubular leg portions, the lower end of the material of each leg portion having a first fold section extending upwardly within the leg por- 75

tion and having a second fold section extending downwardly therefrom between the inside of the leg and said first fold section, and having a third fold section extending upwardly again along the 5 inside of the trousers leg, means for securing the free edge of said third fold section to the inside of the trousers leg, and removable means extending along the upper edge of the first fold section for securing said edge to the inside of the 10 trousers leg, the trousers bottom being foldable exteriorly upwardly to form a cuff, said third fold section being of sufficient length to permit the cuff to be rolled downwardly to lengthen the trousers without exposing the securing means for 15 the free edge of said third fold section.

4. A variable length trousers construction comprising tubular leg portions, the lower end of the material of each leg portion having a first fold section extending upwardly within the leg portion, and having a second fold section extending 20 downwardly therefrom between the inside of the

leg and said first fold section, a tuck on said leg portion having its folded edge projecting downwardly on the exterior of the leg portion, removable means for holding said tuck in position, removable means extending along the upper edge 5 of said first fold section for securing said edge to the inside of the trousers leg, and means for securing the free edge of the material forming the second fold section to the inside of the material of the leg portion, the trousers bottom being foldable exteriorly upwardly to form a cuff which conceals said tuck, the trousers being convertible to greater length by letting out said tuck, and said trousers being formable to still greater length by removing the removable means extending along the upper edge of the first fold section and letting down said edge, and by subsequently folding said edge upwardly exteriorly of the trousers to form a cuff. 10 15
